UNITED STATES PATENT OFFICE.

GUERDON O. JONES, OF BOUTON, IOWA.

TIRE-PRESSURE VALVE AND SIGNAL.

1,270,952.

Specification of Letters Patent. Patented July 3, 1918.

Application filed May 3, 1917. Serial No. 186,149.

To all whom it may concern:

Be it known that I, GUERDON O. JONES, a citizen of the United States of America, and resident of Bouton, in the county of 5 Dallas and State of Iowa, have invented a new and useful Tire-Pressure Valve and Signal, of which the following is a specification.

The object of this invention is to provide means for indicating by a signal or alarm 10 audible to the user when the pressure of air or gas in a pneumatic tire or other container has reached a predetermined degree.

A further object of this invention is to provide means for adjusting, to a visible 15 scale, the parts of a pressure valve so as to permit the introduction of air to a predetermined degree of pressure into a pneumatic tire, or other container, and, when said 20 degree of pressure is attained, to permit the further supply of air to discharge to the atmosphere and in so doing present an audible signal to the user.

A further object of this invention is to provide means for manually testing the operation 25 of a tire-pressure valve, and gage, without taking it apart or dis-assembling it.

A further object of this invention is to provide a simple, convenient and inexpensive construction for valves having combined 30 therewith the characteristics of presenting an audible signal or alarm and means for testing as to operativeness without dis-assembling the parts or any of them.

My invention consists in the construction, 35 arrangement and combination of elements hereinafter set forth, pointed out in my claims and illustrated by the accompanying drawing, in which—

Figure 1 is a side elevation of the complete 40 device. Fig. 2 is a side elevation of the device partly in section on the central line of the casing. Fig. 3 is a cross-section on the indicated line 3—3 of Fig. 1.

In the construction of the device as shown 45 the numeral 10 designates a main or body of a valve casing, which is of generally cylindrical shape and formed with a bore 11 centrally and from end to end thereof. One end portion of the body 10 is formed with 50 an external thread 12 adapted to be attached to a hose or pipe leading from a source of compressed air, gas or other fluid or liquid (not shown). At the opposite end a coupling 13 is pivoted on the body 10 and is 55 formed with an internal thread 14 adapted

to be screwed on a tire-valve casing or stem (not shown), or other inlet of a container into which fluid or liquid is to be introduced under pressure. Any desired means may be employed to connect the coupling 13 to the body 10, and I here show a conventional means consisting of a peripheral flange 15 on the body co-operating with an internal flange 16 on the coupling. Any suitable packing means may be employed in the coupling. A lateral 17, of the valve casing, is formed on and extends laterally from the central portion of the body 10, and said lateral is formed with a central bore 18 extending from end to end thereof and communicating at its inner end with the bore 11. An annular chamber or cavity 19 is formed in the outer end portion of the lateral 17 and the end of said lateral within and bounded by said chamber is smooth, preferably ground, to form a valve-seat 20. A branch or brace member 21 is located obliquely between and formed on or fixed at its ends to the outer end of the lateral 17 and the body 10, the point of application or 70 jointure of the branch to the body being between the lateral and the threaded end portion of said body. The branch 21 is formed with a central bore 22 stopped at one end by the body 10 and communicating at the other end with the annular chamber 19. A whistle-notch 23 is formed in the inner side of the branch 21 and affords communication between the bore 22 and the atmosphere between the lateral 75 and body. An internal thread is formed in the outer end portion of the lateral 17 and extends into the chamber 19 and a wrench-hold 24 is formed on the exterior of said lateral. The casing thus far described may 80 be made in one piece of metal by molding, preferably by the well-known process of die-casting. A barrel 25, of generally cylindrical form, is screwed at one end into the chamber 19 and engages the thread on the 85 interior of the lateral 17. A valve stem 26 is mounted loosely in and centrally of the barrel 25 and is formed with longitudinal ribs 27 (Fig. 3) spaced apart on the periphery of its inner end portion, which inner end 100 portion extends within the outer end of the bore 18, said ribs serving to engage the wall of said bore and steady the stem therein, at the same time permitting air to pass through said bore between said ribs. A disk valve 110

28 is mounted rigidly on the stem 26, near to the ribs 27, and a washer 29, of leather or fiber, is mounted on said stem between the head 28 and the ribs and in contact with said head. The washer 29 is adapted to engage and seat on the valve-seat 20 to close the bore 18 at one end. A pressure spring 30 is coiled on the stem 26 within the barrel 25, and said spring engages or impinges at one end 10 on the head 28 and, when backed as herein-after described, holds the head and washer toward the seat 20. An adjusting screw 31, having a milled head 32, is screwed into the outer end of the barrel 25 and is formed with 15 a central bore from end to end adapted to admit and permit the loose passage therethrough of the stem 26. The inner end of the adjusting screw 31 engages the spring 30 and governs and controls the pressure 20 exerted by said spring on the head 28 and, consequently, the force required to unseat the washer 29 from the seat 20. A ball or handle 33 is mounted, in this instance by screwing, on the outer end of the stem 26 25 and is spaced from the adjusting screw 31 to permit manual adjustment of said screw without contact with said ball. The ball may be employed for manipulation of the valve-stem 26, to unseat the valve and prevent 30 sticking and jamming thereof in use, without dis-assembling the screw, barrel or other parts. An annular groove or depression 34, of considerable length, is formed in the outer end portion of the periphery 35 of the barrel 25 and annular graduations are formed in the bottom of said groove and spaced apart longitudinally of said barrel, which graduations are provided with indices such as 50, 60, 70, 80, 90, 100, and the like, 40 to indicate the pounds or units of pressure required to unseat the valve against the pressure spring. A collar 35 is mounted on the screw 31 and preferably is secured to the inner face of the head 32, and a pointer or 45 index finger 36 is formed on said collar and extends into proximity to one or another of the graduations on the barrel 25. The pointer or index finger 36 is of irregular shape in that it extends radially from the 50 collar 35 to a zone slightly beyond that occupied by the periphery of the outer end of the barrel, is then bent at right angles and extends inwardly parallel with the adjusting screw and to overlapping relation with the depression 34, and then is bent toward the barrel and enters the depression 34. The 55 extremity of the pointer is wedge-shaped and forms a hook which normally prevents removal of the adjusting screw 31 from the barrel 25. In order to remove the screw 31 from the barrel 25, it is necessary first to bend or flex the pointer 36 away from said barrel manually. During the operation of 60 adjusting the pressure of the spring 30, by manipulation of the adjusting screw 26, the

pointer or index finger 26 travels in relation to the graduations in the depression 34 and indicates thereon the force required to unseat the valve; hence the screw may be set to apply any desired and predetermined 70 pressure to said valve.

In ordinary use in relation to a pneumatic tire, the body is permanently attached to an air hose or pipe and, then, is detachably connected to a tire-valve casing or 75 stem. Air, under pressure, is turned through the hose and body and enters the tire through said valve or stem until the required and predetermined pressure is developed in said tire, at which time the pressure acts on and 80 unseats the valve washer 29 from the seat 20, against the pressure of the spring 30. Then the air from the pressure supply escapes to the atmosphere through the seat 20, chamber 19, branch bore 22 and whistle-notch 23, in sequence, and makes an audible 85 signal or whistle, which serves as a notice or alarm to the user who may be busied about other matters. Upon hearing the signal, the user would shut off the air supply 90 and adjust the device to another tire or make other disposition of it.

The use of this device avoids the necessity of frequent testing of the container, such as pneumatic tire, during the operation 95 of replenishing the pressure of air therein; and it also avoids constant attention as the branch and whistle notch provides an effective safety or pop-off for the valve and prevents overcharging of the container. 100

The valve should be manipulated just prior to each use thereof, by draft on the ball 33 to unseat the valve and anticipate sticking or jamming thereof in use.

I do not desire to be understood as limiting myself to the precise construction and arrangement of parts or to the specific use thereof on pneumatic tires, as the same may be modified or the use be varied and extended without departing from my invention. 110

I claim as my invention—

1. A tire-pressure valve, gage and signal, comprising a tubular body, means for securing an air hose to said body, means for securing said body to a valve casing in a tire, a tubular lateral on said body and communicating therewith, a valve-seat in said lateral, the lateral being formed with a chamber surrounding said valve-seat, a branch connected obliquely to said lateral and body, said branch being formed with a bore opening at one end to said chamber, a whistle-notch being formed in said branch, a barrel on said lateral, an adjusting screw 115 in said barrel, a valve stem mounted loosely in said screw, barrel and lateral, a head on said stem within said barrel, a washer on said stem between said head and valve-seat and adapted to engage the latter, and a pres- 120

125

130

sure spring on said stem within said barrel, said spring impinging at its ends on said head and screw respectively.

2. In a device of the class described, a 5 casing formed with a tubular body, a tubular lateral communicating therewith, a tubular branch connecting the body and lateral, said lateral being formed with a valve-seat and also being formed with an annular 10 chamber surrounding said seat and communicating with the bore of the branch, said branch being formed with a whistle-notch, all of said parts being integral.

3. A tire-pressure valve, gage and signal, 15 comprising a tubular body, means for securing an air-hose to said body, a coupling pivoted on said body and adapted to engage a tire-valve-casing, a tubular lateral on said body and communicating therewith, a valve-seat being formed in said lateral, said lateral being formed with an annular chamber surrounding said valve-seat, a branch integrally connected obliquely to said body and lateral, said branch being formed with a bore opening 20 at one end to said annular chamber, said branch being formed with a whistle-notch between the lateral and body, a barrel screwed in said chamber and spaced

from said valve-seat, the axis of the barrel being coincident with the center of the bore 30 of the lateral, an adjusting screw screwed into said barrel in line with said valve-seat and formed with a bore having an axis coincident with the axis of the bore of the lateral, a valve-stem mounted loosely in the 35 bore of the adjusting screw and extending through the barrel into the bore of the lateral and through the valve-seat, said stem also extending outside of the adjusting screw, a handle on the outer end of said 40 stem, longitudinal ribs on the inner end of said stem, a head on said stem within said barrel, a washer on said stem between the head and valve-seat and adapted to seat on the latter, a pressure-spring on said stem 45 within the barrel, said spring impinging at its ends on the screw and head respectively, said barrel being formed with a peripheral depression and also being formed with an annular graduations in the bottom of said depression, a collar mounted on said adjusting screw, and a pointer formed on said collar, said pointer extending to and terminating in wedge-shape in the depression.

GUERDON O. JONES.
